UNITED STATES PATENT OFFICE.

HENRY LEIMAN, OF TAMPA, FLORIDA.

COLLAPSIBLE CIGAR-BOX.

1,053,836.

Specification of Letters Patent. Patented Feb. 18, 1913.

Application filed December 29, 1911. Serial No. 668,422.

To all whom it may concern:

Be it known that I, HENRY LEIMAN, a citizen of the United States, residing at Tampa, in the county of Hillsboro and State 5 of Florida, have invented certain new and useful Improvements in Collapsible Cigar-Boxes; and I do hereby declare the following to be a full, clear, and exact description of the invention, such as will enable others 10 skilled in the art to which it appertains to make and use the same.

My invention relates to improvements in knock down or collapsible cigar boxes.

The invention consists in providing an 15 outside box or carton of paper, or other similar suitable material, and an inside liner of wood which is disconnected from the outside paper box but designed to be readily inserted into position and held in place by the 20 outside paper container without the use of glue or nails.

Among the objects of the invention are the saving of car room in shipping empty boxes from the box factory to the cigar factory 25 and the lessening of the cost of manufacturing the boxes without in any way detracting from the appearance of the box or its utilities.

In the accompanying drawings: Figure 1 30 is a plan view of a paper blank for a box which constitutes the outside of the cigar box. Fig. 2 is a perspective view of the paper box folded in position and showing the wooden cover of the box secured to the 35 paper cover or lid. Fig. 3 is a perspective view of the parts of the wooden box before the same are assembled and placed in position within the body of the paper box. Fig. 4 is a perspective view of the completed box 40 with the wood liner in position and partly broken away at one corner to show the outside paper and one corner fold thereof. Fig. 5 is an end view of the paper box in a partly folded condition. Fig. 6 is an end view 45 showing the paper carton and wooden liner pieces in a completely folded condition ready for shipment. Fig. 7 is a perspective view of a modified form of the box showing the wooden lid disconnected from the paste- 50 board cover. Fig. 8 is a transverse section through the modified form of box and showing the wooden lid about to be placed in position and the attaching flap ready to be inserted between the outside paper carton 55 and the wooden liner; and Fig. 9 is a vertical transverse section through the modified form of box with the wooden lid and at-

taching flap in position when the box is in a completely closed condition.

In my long experience as a manufacturer 60 of cigar boxes I have found that a great deal of car space is lost in shipping empty cigar boxes from the box factory to the cigar factory and also that the operation of assembling the parts of the wooden boxes and 65 either gluing or nailing the same together to form a box and applying securing strips along the same is a more or less expensive operation. The trade demands that cedar wood be employed in the construction of 70 cigar boxes as it is considered of great benefit to the cigars as it imparts a flavor that cannot be supplied in any other way except by housing the cigars. My invention meets this requirement of the tobacco trade and at 75 the same time does away with the difficult problem of transportation besides being less expensive to manufacture than is the ordinary box in use at the present time, inasmuch as all lithographing work may be done 80 on the paper box or carton before it is put together, thereby causing a great saving over the present method of pasting the different lithographed pieces on the "nailed up box", which requires expert hand workers. 85

1 in the drawings represents a paper carton or box which is preferably made from a single piece of material as shown in Fig. 1, which is scored and folded into a box or carton as shown in Fig. 2. The ends 2 of 90 the carton are preferably secured to the sides of the carton as shown in Fig. 2. The ends of the carton are also scored at 3-3 as shown in Figs. 1 and 2 for the purpose of permitting the ends of the carton to be folded 95 inwardly upon the body of the carton as shown in Fig. 5. By this means, together with the scoring at the juncture of the sides and ends with the bottom of the carton the carton may be folded into a very compact 100 condition together with the wooden liner ready for transportation as shown in Fig. 6.

To the cover 4 of the paper carton is preferably pasted the wooden cover 5 of the box or liner. This cover 5, as are the rest of the 105 pieces of wood constituting the liner or wooden box, is constructed of wood and preferably cedar wood for the reasons heretofore set forth. By permanently securing the wooden cover 5 to the paper lid or cover 110 4 the necessity for separately handling this wooden lid in building up the box is avoided and the liability of losing the same prevented. A gummed extension or flap 6 is pro-

vided which projects from the front edge of the paper cover and when the lid or cover is down the flap 6 is secured in position to the body of the box by inserting it 5 between the front side of the paper box and the front side of the wooden liner and pasting it to the inside face of said front paper side.

The corners of the paper carton as well 10 as the edges thereof may be strengthened by having strips of paper pasted on the same as in the case of an ordinary cigar box. Furthermore, the paper carton may be lithographed and printed in exact imitation of 15 an ordinary wooden cedar cigar box so as to give it every appearance on the outside of being a cedar cigar box having the usual wording and decoration.

In order to give rigidity to the outside 20 paper carton 1 and at the same time secure a cedar lining to the box I provide side and end pieces 7 and a bottom piece 8 as shown in Fig. 3 which are designed to be slipped into position in the outside paper 25 carton 1, as shown in Fig. 4. I preferably bevel the vertical edges of the side and end pieces 7 so that when they are slipped into position they will be securely held in place without the necessity of gluing or nailing. 30 The outside paper carton is made of stiff cardboard and being reinforced at the corners enables the pieces 7 to be snugly fitted in position and held from moving outwardly, and the beveled edges prevent 35 the wooden piece from moving inwardly, so that a strong, permanent cedar box or lining within an outside paper carton is secured having all the advantages of an ordinary cedar cigar box with the added advantages 40 of being cheaper to construct and the ability to ship a much greater quantity of the same in a knocked down condition than is possible with ordinary cigar boxes in a built up condition.

45 In operation the cartons are received at the cigar factory either in a folded condition as shown in Fig. 6 or in a flat condition as shown in Fig. 1 with the cedar pieces 7 and 8 in an unassembled condition. Operators take the paper blanks and fold them 50 into a carton, as shown in Fig. 2, and then quickly insert the cedar bottom 8 and then the sides and ends 7 and the box is then in a condition to be filled with cigars. After 55 the box is filled the lid or cover is brought down and flap 6 pasted to the inside of the front edge of the paper box. If desired nails may be passed through the combined paper and wood cover or lid into the wooden 60 sides and ends 7 as additional securing means.

In Figs. 7, 8 and 9 I have shown a modified form of the box, the only difference be-

ing that the wooden lid or cover 5 is not attached to the paper cover 4 but is made separate therefrom and is placed in position on top of the wooden sides and ends after the box is made up and the cigars placed in position within the box. The paper cover is then brought down and secured in position 70 as heretofore described.

Having now described my invention what I claim as new and desire to secure by Letters Patent is:

1. A collapsible cigar box comprising an 75 inflexible bottom, inflexible side and end pieces mitered at their corners and resting upon the bottom, a paper carton embracing the inflexible members and maintaining such members removably in association, said carton having edges extending above the edges of the side and end pieces and producing a rabbet, and a cover member proportioned to be disposed upon the side and end pieces within the rabbet.

85 2. A collapsible cigar box comprising a carton composed of flexible material embodying a bottom, sides and end pieces, some of said members being scored to permit the side and end pieces to fold inwardly, 90 an inflexible bottom member proportioned to be disposed within the carton, inflexible side and end members having mitered engaging corners proportioned to be removably inserted within the carton and rest on 95 the inflexible bottom and to maintain the carton in distended condition and to be maintained in relation by the surrounding carton, an inflexible cover member proportioned to rest on the top edges of the side 10 and end inflexible pieces, and a cover section hinged to the carton adapted to maintain the inflexible cover portion in such association.

10 3. A receptacle comprising an inflexible bottom, inflexible side and end pieces mitered at their corners and resting on the bottom, a carton composed of flexible material embracing the inflexible members and maintaining such members removably in 11 mitered relation and being maintained in extended position by such side and end members, said carton having edges extending above the edges of the side and end pieces and producing a rabbet, an inflexible 12 cover member proportioned to be disposed upon the side and end pieces within the rabbet, and a cover carton portion flexibly connected with the sides of the carton and inclosing the inflexible cover member.

12 In testimony whereof I affix my signature in presence of two witnesses.

HENRY LEIMAN.
